IMPLEMENT FOR REMOVING BACKS OF
WATCHCASES

Ernst E. Thoms, Dayton, Ohio

Application March 27, 1947, Serial No. 737,525

7 Claims. (Cl. 81—6)

1

This invention relates to an implement for removing the backs of watch cases, and for like purposes.

In certain types of watches the back of the watch case is screwed into the body of the case and it is often very difficult to remove the same. The back is frequently provided with peripheral notches or flats for engagement by a removing implement. Various implements have been provided for removing the back of such a watch case but, for the most part at least, they have not been entirely satisfactory.

One object of the invention is to provide a simple efficient implement with which force can be exerted on the back of the watch case sufficient to release a tightly set back without danger of scratching or otherwise marring the back.

A further object of the invention is to provide such an implement which can be applied to watch case backs of various kinds and sizes.

A further object of the invention is to provide such an implement in which the back engaging elements are removable to permit the substitution of other elements of a different size or shape.

A further object of the invention is to provide such an implement having work engaging elements which are adjustable to engage the back of the watch case either at two points or at three points.

A further object of the invention is to provide such an implement having means for gripping and removing a watch case back which is not provided with notches or flats.

A further object of the invention is to provide such an implement which is of a strong durable and compact construction and can be produced at a relatively low cost.

Other objects of the invention may appear as the implement is described in detail.

In the accompanying drawings Fig. 1 is a perspective view of an implement embodying the invention; Fig. 2 is a longitudinal section taken on the line 2—2 of Fig. 1; Fig. 3 is a transverse section taken on the line 3—3 of Fig. 1; Fig. 4 is a detail view of one of the back engaging elements; Fig. 5 is a section taken on the line 5—5 of Fig. 4; Fig. 6 is a perspective view of a third or supplemental back engaging element; Fig. 7 is a perspective view partly broken away showing the implement provided with a modified form of back engaging elements; Fig. 8 is a perspective view of one of the back engaging elements of Fig. 7; and Fig. 9 is a side view, partly in section of a further modification showing the im-

2

plement equipped with a single back engaging element.

In these drawings I have illustrated one embodiment of the invention, together with certain modifications thereof, and have shown the same as designed primarily for removing the back of a watch case, but it is to be understood that the implement may take various forms and may be used for various purposes without departing from the spirit of the invention.

In the embodiment here illustrated the implement comprises a supporting member 10 which is preferably in the nature of an elongate flat plate of sufficient thickness to provide the same with the necessary rigidity. On this supporting member are mounted a plurality of back, or work, engaging elements which are adjustable with relation one to the other. In the present device the supporting member 10 is provided with a longitudinal slot 11 having at one end thereof an enlargement or opening 12 of a width substantially greater than the width of the slot. Mounted in this slot are two work engaging elements 13 and 14, the element 13 being held against outward movement, as by contact with the end wall of the slot, and the element 14 being adjustable toward and from the element 13. Each element has an intermediate portion 15 of a width approximating the width of the slot so that the element can be inserted in and moved lengthwise of the slot. Each element is provided above and below the supporting member with parts, such as flanges 16, of a width greater than the width of the slot, so as to support the elements against vertical movement in the slot, but these parts 16 are of a width less than the width of the opening 12, so that the elements 13 and 14 can be inserted in or removed from the slot. Thus by moving the elements successively into the opening 12 and then moving the same through that opening they may be quickly and easily removed from the supporting member. Each element is provided at at least one end thereof with a work engaging part 17, as shown in Figs. 2 and 4. As there shown the parts 17 are in the nature of small diameter projections depending from the lower ends of the respective elements and are preferably substantially semi-circular in form so that they may engage either flats or notches in the peripheral edge of the back of a watch case. If desired the elements may be provided at their opposite ends with other work engaging parts 18 of a size or shape different from the parts 17.

The intermediate portion 15 of the work engaging element 14 is preferably non-circular to prevent the rotation thereof in the slot, and is here shown as square in cross section, so that it can slide freely in the slot. This slideable element may be adjusted toward and from the opposed element 15 in any suitable manner, as by a screw threaded rod 19 mounted in a threaded opening 20 in the end of the supporting member and provided at its outer end with a knob 21 by which it may be rotated. The inner end of the rod bears against the slideable element 14 and that element is held in contact with the rod by a spring 22 interposed between the same and the normally stationary element 15. Thus by properly adjusting the work engaging elements 13 and 14 the work engaging parts 17 thereof may be positioned to engage diametrically opposite flats on or notches in watch case backs of various sizes, and by reversing the positions of the work engaging elements, or by removing one set of elements and substituting another set therefor, the device may be accommodated to a wide range of backs. In operation the watch from which the back is to be removed may be held in one hand and the supporting member gripped in the other hand and force applied thereto in a direction to unscrew the back. Or the watch may be gripped in a vise, or the like, and the implement supported by one hand in proper engagement with the back and rotative force applied thereto by the other hand, the supporting member being in the present instance provided with a rod or handle 23 at that end opposite the rod 19.

In the backs of some watch cases the notches or flats are evenly spaced but are of unequal number, so that they have no diametrically opposite notches or flats which can be engaged by the opposed work engaging elements. To accommodate the device to such a back I have provided a third or supplemental work engaging element 24 which is rigidly secured to and depends from an arm 25 which is mounted on the supporting member 18 for adjustment with relation to the work engaging elements 13 and 14. In the arrangement shown the arm 25 rests upon the upper surface of the supporting member and is provided with a longitudinal slot 26, the arm being connected with the member by a screw 27 threaded into the supporting member and having a head 28 of greater width than the slot, so that by loosening the screw the arm and, therefore, the work engaging element 24 can be adjusted to various positions both transversely of the supporting member and about the axis of the screw 27. Thus by a proper adjustment of the third element the three elements can be caused to engage three notches, or flats, in the back of the case.

In Fig. 7 I have shown the work engaging elements as having work engaging parts of such a character that they may engage and tightly grip the peripheral edge of a watch case back regardless of whether the back is or is not provided with flats or notches. For this purpose the work engaging elements are provided on one side of, in the present instance below, the supporting member with arcuate parts 29 the lower portions of which are provided with inner beveled surfaces 30, these surfaces being serrated or otherwise roughened to enable them to tightly grip the periphery of a watch case back. Thus by adjusting the elements the work engaging parts can be moved into gripping contact with the periphery of the back so that the back will be

caused to rotate with the implement when force is applied to the latter.

In Fig. 9 I have shown a form of the device in which the arcuate work engaging parts, or jaws, are combined to form a single annular structure 31 the lower portion of which is provided with an inner beveled and roughened surface 32. This annular structure is adapted to be connected with a supporting member for rotation thereby so that when the beveled edge thereof is placed in engagement with the watch case back of a corresponding size and downward pressure is exerted on the supporting member the work engaging part will firmly grip the back and cause it to rotate with the implement. The work engaging structure 31 may be connected with the supporting member in a suitable manner, in the present instance it is designed for attachment to the supporting member 10 and is provided in its upper portion with diametrically opposite sockets 33 adapted to receive the lower end portions of the work engaging elements 13 and 14, when these have been properly adjusted with relation one to the other or to receive any suitable devices which may be substituted for said work supporting elements.

While I have shown and described one embodiment of my invention, together with certain modifications thereof, I wish it to be understood that I do not desire to be limited to the details thereof as various modifications may occur to a person skilled in the art.

Having now fully described my invention, what I claim as new and desire to secure by Letters Patent is:

1. An implement for removing the back of a watch case, comprising a supporting member having a slot therethrough and having at one end of said slot an opening of a width greater than the width of said slot, two elements slidably supported in said slot, each element having above and below said supporting member parts of a width greater than the width of said slot and less than the width of said opening, one of said elements being held normally against movement lengthwise of said slot, spring means for resisting the movement of the other of said elements toward the first mentioned element, and a self-locking adjusting device mounted on said supporting member and engaging the last mentioned element to move the latter toward the first mentioned element, said elements having below said supporting member means for engaging and rotating the back of a watch case.

2. An implement for removing the back of a watch case, comprising a supporting member having a slot therethrough, an element supported in said slot at one end thereof, a second element supported in said slot for movement toward and from the first mentioned element, a spring confined between said elements to retain the first mentioned element at said end of said slot and to urge the last mentioned element toward the other end of said slot, an elongate screw threaded adjusting member mounted in said supporting member, extending into said slot and engaging the last mentioned element to move the latter against the action of said spring toward the first mentioned element, said elements having cooperating parts below said supporting member to engage and rotate the back of a watch case.

3. An implement for removing the back of a watch case, comprising a supporting member having a slot therethrough, an element supported in said slot at one end thereof, a second element

supported in said slot for movement toward and from the first mentioned element, a spring confined between said elements to retain the first mentioned element at said end of said slot and to urge the last mentioned element toward the other end of said slot, an elongate screw threaded adjusting member mounted in said supporting member, extending into said slot and engaging the last mentioned element to move the latter against the action of said spring toward the first mentioned element, said elements having co-operating parts below said supporting member to engage and rotate the back of a watch case, said adjusting member having a part extending beyond one end of said supporting member to form a handle, and a second handle secured to the other end of said supporting member.

4. An implement for removing the back of a watch case, comprising a supporting member having a slot therethrough, an element supported in said slot at one end thereof, a second element supported in said slot for movement toward and from the first mentioned element, a spring confined between said elements to retain the first mentioned element at said end of said slot and to urge the last mentioned element toward the other end of said slot, an elongate screw threaded adjusting member mounted in said supporting member, extending into said slot and engaging the last mentioned element to move the latter against the action of said spring toward the first mentioned element, said elements having below said supporting member opposed arcuate work engaging parts to grip the peripheral portion of the back of a watch case and rotate the latter.

5. An implement for removing the back of a watch case, comprising a supporting member having a slot therethrough, two elements slidably supported in said slot, one of said elements being held normally against movement lengthwise of said slot, spring means resisting the movement of the other of said elements toward the first mentioned element, a self-locking adjusting device mounted on said supporting member and engaging the last mentioned element to move said element against the action of said spring means toward said first mentioned element, said elements having parts extending below said supporting member, and an annular work engaging member having means whereby it may be detachably connected with said parts of said elements and having a beveled inner surface to engage the back of a watch case.

6. An implement for removing the back of a watch case, comprising a supporting member having a slot therethrough, two elements slidably supported in said slot, one of said elements being held normally against movement lengthwise of

said slot, spring means resisting the movement of the other of said elements toward the first mentioned element, a self-locking adjusting device mounted on said supporting member and engaging the last mentioned element to move said element against the action of said spring means toward said first mentioned element, a member mounted on said supporting member for adjustment transversely to said slot, means for securing said member in adjusted positions, and a third element mounted on said adjustable member for movement therewith and in a position substantially parallel with said two elements, the three elements having below said supporting member cooperating parts to engage and rotate the back of a watch case.

7. An implement for removing the back of a watch case, comprising a supporting member having a slot therethrough, an element supported in said slot at one end thereof, a second element supported in said slot for movement toward and from the first mentioned element, a spring confined between said elements to retain the first mentioned element at said end of said slot and to urge the last mentioned element toward the other end of said slot, an elongate screw threaded adjusting member mounted in said supporting member, extending into said slot and engaging the last mentioned element to move the latter against the action of said spring toward the first mentioned element, an arm mounted on said supporting member for adjustment both transversely to said supporting member and about an axis spaced laterally from the line of movement of said adjustable element and projecting beyond one side of said supporting member, an element carried by the projecting portion of said arm and substantially parallel with the first mentioned elements, said elements having below said supporting member cooperating parts to engage and rotate the back of a watch case.
